UNITED STATES PATENT OFFICE.

SALVADOR BARRILE, OF MEDFORD, MASSACHUSETTS.

CONVERTIBLE SOFA.

Application filed October 25, 1922. Serial No. 596,772.

To all whom it may concern:

Be it known that I, SALVADOR BARRILE, a citizen of the United States, residing at Medford, county of Middlesex, State of Massachusetts, have invented a certain new and useful Improvement in Convertible Sofas, of which the following is a specification, reference being had therein to the accompanying drawings.

10 The invention relates to a new and useful improvement in convertible sofas which are adapted to be converted from a sofa into a bed. It is more especially intended for use in that class of sofas which are 15 termed davenports, having a drop back so that the seat and back of the sofa together will form a bed of the width equal to the width of the seat and the height of the back, the headboard being formed as 20 a part of one end of the sofa.

In convertible bed sofas heretofore made an objection has been that when the back is dropped down there is a gap between that portion of the bed formed by the upholstered back and the portion which is formed by the seat of the sofa. One object of the present invention is to provide such a construction that when the back is dropped down to form the bed, the upholstered portion of the back will come as close to the upholstered portion of the seat as the two members of a two-part mattress of an ordinary bed. Another object of 35 the invention is to provide mechanism of easy manipulation for dropping the back when it is desired to convert the sofa into a bed. Other features of the invention will be more particularly set forth in the specification and in the claims hereinafter.

40 The invention will be fully understood from the following description when taken in connection with the accompanying drawings, and the novel features thereof will be pointed out and clearly defined in the claims 45 at the close of this specification.

In the drawings, Fig. 1 is a front elevation of a sofa embodying the invention, the upholstery being removed for the purpose of more plainly showing the inside 50 mechanism.

Fig. 2 is a perspective view showing one end and a portion of the back of the article, as shown in Fig. 1.

Fig. 3 is a section on line 3—3 of Fig. 55 2 on a larger scale.

Fig. 4 is an end view of the sofa with

the upholstered seat and back in place but partly broken away to show the mechanism for dropping the back.

Fig. 5 is an end view showing the parts 60 of Fig. 4 but with the back in the dropped-down position to convert it into a bed.

Referring now to the drawings, 1 and 2 represent respectively the front and rear rails of the framework for supporting the seat of the sofa, and 3—3 the lower end rails of the framework which connect the front and rear rails 1—2 at each end thereof. The framework also has the front and rear posts 4, 5 at each end, which at their 70 lower ends are connected by the end rail 3 and are also connected by the arm rails 6. An end panel board 15 is attached to the said end rails. The back comprises a framework having two vertical end rails 75 7, 7 and the top and bottom rails 8—9. The back framework is also preferably provided with intermediate vertical bars 10—10 to divide the back portion of the frame into panels and stiffen the frame. These panels 80 are adapted to receive the upholstered back members 11 and the seat receives upholstered cushions 12. A headboard 13 is longitudinally slideable on the ledge 14 for the purpose of extending the headboard of 85 the bed when the back is folded down, as will be hereinafter explained. When said headboard 13 slides back, it will form a rear extension of the end board 15 which will form the front part of the headboard. 90

A segment gear 16 which is preferably substantially a quadrant is made fast to the upright end rail 7 of the back frame as shown in Figures 4 and 5, by any suitable means, the means shown being screws 95 17—17. The back frame together with the segment gear 16 is pivoted at 18 to the slide plate 21 at each end of the sofa, it being understood that each end of the sofa is constructed similar to the end shown in Figure 100 2, and that there is a corresponding segment gear and other operating mechanism, as will be hereinafter described, at each end.

A plate 19 is made fast on the upper edge of the lower end rail 3 and has on its upper face a toothed rack 20. A slide plate 21 is formed with a longitudinal slot 22 and is supported by the plate 19 by means of the engagement of the plate 19 with the longitudinal slot 22. Thus the slide plate 21 is 110 supported in part by the fixed plate 19 and in part by the guide plate 27. The slot 22 is

of greater length than the plate 19 so that the slide plate is capable of a longitudinal movement, the plate 19 serving as a track. A train of gears 24, 25, 26 is journalled in said plate 21, the gear 26 at one end of the train engaging with the teeth of the segment gear 16, and the gear 24 at the other end of the train engaging with the teeth of the rack 20. The plate 27 is secured to the bottom 10 end rail 3, as by screws 28-28, and is formed with a grooved guide portion 29. The slide plate 21 is formed with a fin or flange 30 which engages in the groove of the grooved portion 29 to aid in supporting and 15 guiding the slide plate 21, thus aiding the rack plate 19 in supporting the slide plate.

Means are provided for retaining the sofa back in its upright position when the sofa is to be used merely as a sofa and not as a bed, 20 but which can be released to allow the back to be turned down.

Any suitable means may be provided for that purpose. That shown in the drawings is as follows:—

25 A slide bolt 31 passes slidably through a hole in the upright end 7 of the back frame of the sofa and is adapted to engage with a slot 32 in a block 33 mounted on the top of the rear end post 5. Said bolt also passes 30 through a hole in the downwardly depending hanger 34 secured to the top back rail 8. A spring 36 coiled around the said bolt and having one end abutting against the end back rail 7 and its other end abutting 35 against the said hanger 34, normally holds the bolt in the slot 32, so as to hold the sofa back in its upright position. A crank shaft 37 is pivotally mounted at 38 in a bearing on the under side of the back top rail 8, the 40 said crank shaft being rotatable on its axis and is provided with a crank arm 39 so that it may be turned by hand. Mounted on the upright arm of said crank shaft 37 is a disk 40. The bolt 31 has a downwardly depending 45 arm 41 at its end which engages with a hole in said disk 40. When said crank shaft 37 is turned on its axis the disk 40 will be rotated in a horizontal plane, thereby causing the bolt 31 to be retracted and disengaged from engagement with the slot 32, leaving the entire back frame to drop back. There is also a locking bolt 36 for the opposite end of the back, and means are provided 50 whereby both bolts will be operated together by means of the crank 39. The means provided are as follows:—

The said locking bolt consists of a rod 35 which passes loosely through a downwardly depending hanger 42 secured to the top back 60 rail 8, said rod 35 having a downwardly depending finger 43 which engages with a hole in the disk 40. The other end of said rod 35 passes through a hole in the right hand end rail 7 of the back and engages with a socket 65 in a block 33 at the top of the right hand

rear post 5. (See Fig. 1.) When the crank 37 is turned to release the bolt 31, the rod 35 will also be moved by reason of its connection with the disk 40, and thereby release it from locking engagement. A hanger 34 70 and spring 36 are employed in connection with bolt 41 similar to those employed with bolt 31.

The sofa back has two folding legs, one at each end thereof, which when the back 75 is dropped down to convert the sofa into a bed will serve as legs. As shown in the drawings, each of the end bars 7 of the back has a folding leg 44 pivotally connected therewith at 45, the said leg being opened 80 out to stand on the floor when the sofa back is folded down, said legs 44 being of sufficient length to hold the sofa back when turned down into its horizontal position at the same level as the seat portion of the 85 sofa. A link 46 is pivotally connected at one end to the said leg 44 and at its other end to the post 5 of the sofa, so as to maintain the folding leg 44 against spreading when the sofa is converted into a bed, as shown 90 in Figure 5.

When it is desired to convert the sofa into a bed, the crank arm 39 will be turned so as to rotate the crank shaft 40 and thus 95 release the bolts at each end of the back from locking engagement with the sockets in the rear posts 5. The back will then be easily turned down on its pivots 18 at its opposite ends, the back being allowed to drop down into horizontal position. The turning down of the sofa back on its pivots will also partially rotate the segment gears 16 through an angle of about 90 degrees from the position shown in Figures 2 and 4 into the position shown in Figure 5. This will 100 give rotation to the train of gears 26, 25 and 24. As previously stated, the teeth of the gear 24 mesh with the teeth of the rack 20. Inasmuch as the rack is stationary and the 105 plate 21 on which the train of gears is mounted is slidable, the effect of the rotation of the gear 24 will be to cause the plate 21 to slide forward in its guides, and the folding legs 44 will be turned down into the 110 upright position as shown in Figure 5, limiting the drop of the sofa back so that the 115 said sofa back will be in the same plane as the seat of the sofa.

The forward sliding movement of the 120 plate 21 will bring the lower edge of the upholstered sofa back slightly forward when the back is turned down so that when it comes down into horizontal position the then forward edge of the upholstered back 11, which before the back was turned down was 125 at the bottom as shown in Figure 4, will be drawn forward into flush engagement with the rear edge of the seat cushion 12. If it were not for this forward movement of the sofa back there would be a gap between the 130

two upholstered members 11 and 12. The headboard extension 13 will then be pulled backward by hand. The headboard is shown as provided with a finger hole 49 for that purpose.

What I claim is:

1. A convertible sofa bed having a seat, a back and ends, a slide member mounted on each of the end members of the sofa frame

10 in such manner as to be slidable forward or back, a pivot connection between the said slide and the lower part of the back, whereby the back member is permitted to be turned down on said pivot, and means where-

15 turned down on said pivot, and means whereby when the back is turned on its pivot the said slide will be moved forward automatically and thereby bring the lower edge of the sofa back forward to meet the rear edge of the sofa seat.

20 2. A convertible sofa bed having a seat, a back, and upright end members, the seat and back being upholstered, a slide member mounted on each of the end members in such manner as to be slidable forward or back, a

25 manner as to be movable forward or back, a pivot connection between the said slide and the lower part of the back, whereby the back member is permitted to be turned down on said pivot, and means whereby when the back is turned down on its pivot the said

30 slide will be moved forward automatically and bring the lower edge of the upholstered back forward to meet the rear edge of the upholstered sofa seat.

3. A convertible sofa bed having a seat, a back and ends, a slide member mounted on each of the end members of the sofa frame in such manner as to be slidable forward or back, a pivot connection between the said

40 slide and the lower part of the back, whereby the back member is permitted to be turned down on said pivot, a segment gear rigidly connected with the back frame, a train of gears mounted on said slide, one of said

45 gears meshing with said segment gear, and a toothed rack rigidly secured to the end of the sofa, one of the gears of said train meshing with said rack whereby when the back

is turned down on its pivot the said slide will be given a forward movement and thereby bring the lower edge of the sofa back forward when the upper edge of the sofa back is brought down.

4. A convertible sofa bed having a seat, a back and ends, a slide member mounted on each of the end members of the sofa frame in such manner as to be slideable forward or back, a pivot connection between the slide members and the ends of the back.

the said slide and the lower part of the back, whereby the back member is permitted to be turned down on said pivot, a segment gear rigidly connected with the back frame, a train of gears mounted on said slide, one

65 of said gears meshing with said segment gear, and a toothed rack rigidly secured to the end of the sofa, one of the gears of said

train meshing with said rack, whereby when the back is turned down on its pivot the said slide will be given a forward movement and thereby bring the lower edge of the sofa back forward when the upper edge of the sofa back is brought down, the said slide being formed with a longitudinal guide slot, said rack being mounted upon a guide member which passes through said slot and is secured to the end of the sofa. 70 75

5. A convertible sofa bed having a seat, a back and ends, a slide member mounted on each of the end members of the sofa frame in such manner as to be slidable forward or back, a pivot connection between the said slide and the lower part of the back, whereby the back member is permitted to be turned down on said pivot, a segment gear rigidly connected with the back frame, a train of gears mounted on said slide, one of said gears meshing with said segment gear, a toothed rack rigidly secured to the end of the sofa, one of the gears of said train meshing with said rack, whereby when the back is turned down on its pivot the said slide will be given a forward movement and thereby bring the lower edge of the sofa back forward when the upper edge of the sofa back is turned down, the said slide being formed with a longitudinal guide slot, said rack being mounted upon a guide member which passes through said slot and is secured to the end of the sofa, said slide plate being provided with a laterally extending flange and a grooved guide plate secured to the end frame of the sofa with which said guide flange on the sliding plate engages.

6. A convertible sofa bed having a seat, a back and upright end members, the seat and back being upholstered, a slide member mounted on each of the end members in such manner as to be slideable forward or back, a pivot connection between the said slide and the lower part of the back, whereby the back member is permitted to be turned down on said pivot, means whereby when the back is turned down on its pivot the said slide will be moved forward automatically and bring the lower edge of the upholstered back forward to meet the rear edge of the upholstered sofa seat, and folding legs connected with the back, which when the back is turned down are automatically opened out to support the back side of the bed formed by the sofa back. 105 110 115 120

7. A convertible sofa having a seat, a back and ends, a slide member mounted on each of the end members of a sofa frame in such manner as to be slidable forward or back, a pivot connection between the said slide and the lower part of the back, whereby the back member is permitted to be turned down on said pivot, latch mechanism for normally holding the back locked against being fold- 125 130

ed down, said latch mechanism being releasable to permit the back member to be turned down, and means whereby when the back is turned down on its pivot said slide 5 will be moved forward automatically and thereby bring the lower edge of the sofa back forward to meet the rear edge of the sofa seat.

8. A convertible sofa bed having a seat, 10 a movable back and fixed ends, a slide member mounted on each of the end members of the frame in such manner as to be slidable forward or back, a pivot connection between said slide and the lower part of the said

movable back, whereby the back member is 15 permitted to be turned down on its pivot, gear connection between the said back frame and the said slide and a gear connection between the said slide and the fixed end, whereby when the back is turned down on its pivot the said slide will be given a forward movement automatically and thereby automatically move forward the lower edge of the sofa back when the upper edge of the sofa back is turned down. 20

25

In testimony whereof I affix my signature.

SALVADOR BARRILE.
